(57) **CLAIM**

The ornamental design for a hookless shower liner fastener, as shown and described.

DESCRIPTION

FIG. 1 is a front perspective view of a hookless shower liner fastener in accordance with my new design;

FIG. 2 is a front elevational view thereof;

FIG. 3 is a left-side elevational view thereof;

FIG. 4 is a right-side elevational view thereof;

FIG. 5 is a top plan view thereof; and,

FIG. 6 is a bottom plan view thereof.

The broken lines in the figures are for illustrative purposes only and form no part of the claimed design.

The rear elevational view of the hookless shower liner fastener is not shown in the drawings or described in the specification and, therefore, forms no part of the claimed design.
